DESIGN FOR A CORSET.

Design No. 12,448, dated September 6, 1881.

UNITED STATES PATENT OFFICE.

JAMES BOWERS, OF NEWARK, NEW JERSEY.

DESIGN FOR A CORSET.

SPECIFICATION forming part of Design No. 12,448, dated September 6, 1881.

Application filed July 11, 1881. Term of patent 3½ years.

To all whom it may concern:

Be it known that I, JAMES BOWERS, a resident of Newark, in the county of Essex and State of New Jersey, have invented and produced a new and original Design for Corsets; and I do hereby declare the following to be a full, clear, and exact description of the invention, such as will enable others skilled in the art to which it appertains to make and use the same, reference being had to the accompanying illustration, and to letters of reference marked thereon, which form a part of this specification.

The accompanying photographic illustration clearly indicates my design for a corset, the leading features of which consist in having diagonal lines of stitching arranged in that portion of said corset lying over the hips of the wearer, in rows which widen as they approach the bottom of the corset, and which are separated by vertical stitches, as will be more fully set forth and claimed.

In the photograph, *a a* represent rows of diagonal or oblique lines of stitches running outwardly and upwardly from a central row or rows, *b*, as will be clearly seen. The diagonal lines *a a*, if produced until they met, would form angles at the center line, *b*, as will be clearly understood. The lines of stitching form pockets in the corset, into which are inserted bones, steels, or other stiffeners, which produce raised ridges upon the outer face of the same, as clearly

shown in the figure. The rows of oblique stitching *a a* are narrowest at the top and widen as they approach the bottom edge of the corset, thus having the form of a gore, as indicated, and thus the general appearance of the design is that of a gore of oblique ridges arranged in rows, the lines of one row running at angles with that of the adjacent row, and said rows separated by vertical ridges, said gore lying in the corset over the hip of the wearer.

I do not wish to limit myself to two rows of stitches *a a*, nor to oblique ridges having central vertical ridges, nor, finally, to the gore-shaped ridged portion; but

What I claim, and wish to secure by Letters Patent, is—

The design for a corset, consisting of rows of parallel ridges running obliquely and upwardly from a central ridge or ridges, *b*, all in that portion of the corset over the hip of the wearer.

In testimony that I claim the foregoing I have hereunto set my hand this 28th day of June, 1881.

JAS. BOWERS.
